(57) **CLAIM**
I claim the ornamental design for a deck post, as shown and described.

DESCRIPTION

FIG. 1 is a perspective illustration of a deck post according to the invention.

FIG. 2 is a front view of the deck post of FIG. 1 (back, left and right views are identical to this front view).

FIG. 3 is detailed front view of an upper portion of the deck post of FIG. 1; and,

FIG. 4 is a detailed front view of a central portion of the deck post of FIG. 1.
